Term of patent 14 years

(Cl. D4—3)

To all whom it may concern:

Be it known that I, Gertrude Levin, a citizen of the United States of America and resident of New York, county and State of New York, have invented a new, original, and ornamental Design for a Combination Toothbrush, Tumbler, and Tooth Paste Tube Holder of which the following is a specification, reference being had to the accompanying drawing, forming a part thereof, in which

Fig. 1 is a side elevational view of a combination toothbrush, tumbler, and tooth paste tube holder embodying my design, with a tumbler, illustrated in dotted lines, in position thereon;

Fig. 2 is a front view thereof;

Fig. 3 is a top view thereof, and

Fig. 4 is a rear view in perspective thereof.

I claim:

The ornamental design for a combination toothbrush, tumbler, and tooth paste tube holder, as shown and described.

GERTRUDE LEVIN.
